(57) **CLAIM**

The ornamental design for a lens cap for camera, as shown and described.

DESCRIPTION

FIG. 1 is a front, bottom, right perspective view of a first embodiment of a lens cap for camera showing my new design, a front, top, left perspective view thereof being an identical image;

FIG. 2 is a front elevational view thereof;

FIG. 3 is a rear elevational view thereof;

FIG. 4 is a bottom plan view thereof, a top plan view being a mirror image;

FIG. 5 is a right side elevational view thereof, a left side elevational view being a mirror image;

FIG. 6 is a front, bottom, right perspective view thereof, wherein the lens cap wall portion is removed, for ease of illustration, the front, top, left perspective view being identical;

FIG. 7 is a cross sectional view thereof cut along the line 7-7 of FIG. 2;

FIG. 8 is an enlarged portion view taken along line 8-8 of FIG. 7;

FIG. 9 is an enlarged portion view taken along line 9-9 of FIG. 7;

FIG. 10 is a cross sectional view thereof cut along the line 10-10 of FIG. 2;

FIG. 11 is an enlarged portion view taken along line 11-11 of FIG. 10;

FIG. 12 is an enlarged portion view taken along line 12-12 of FIG. 10;

FIG. 13 is an enlarged portion view taken along lines 13-13 and 13'-13' of FIG. 2;

(Continued)

FIG. 14 is an enlarged portion view taken along lines 14-14 and 14'-14' of FIG. 13;
 FIG. 15 is an enlarged portion view taken along line 15-15 and 15'-15' of FIG. 13;
 FIG. 16 is an enlarged portion view taken along line 16-16 and 16'-16' of FIG. 13;
 FIG. 17 is an enlarged portion view taken along line 17-17 and 17'-17' of FIG. 2;
 FIG. 18 is an enlarged portion view taken along line 18-18 and 18'-18' of FIG. 17;
 FIG. 19 is an enlarged portion view taken along line 19-19 and 19'-19' of FIG. 17;
 FIG. 20 is an enlarged portion view taken along line 20-20 and 20'-20' of FIG. 17;
 FIG. 21 is a front, bottom, right perspective view of a second embodiment of a lens cap for camera showing my new design, front, top, left perspective view thereof being an identical image;
 FIG. 22 is a front elevational view thereof;
 FIG. 23 is a rear elevational view thereof;
 FIG. 24 is a bottom plan view thereof, a top plan view being a mirror image;
 FIG. 25 is a right side elevational view thereof, a left side elevational view being a mirror image;
 FIG. 26 is a cross sectional view thereof cut along the line 26-26 of FIG. 22;
 FIG. 27 is an enlarged portion view taken along line 27-27 of FIG. 26;
 FIG. 28 is a cross sectional view thereof cut along the line 28-28 of FIG. 22; and,
 FIG. 29 is an enlarged portion view taken along line 29-29 of FIG. 28.
 The broken lines illustrating portions of the lens cap for camera form no part of the claimed design. Dot-dash broken

lines defining the boundaries of the claimed design form no part of the claimed design.
